Primary Examiner — Eric Goodman*Assistant Examiner* — Luqman McNeil(74) *Attorney, Agent, or Firm* — Collard & Roe, P.C.(57) **CLAIM**

The ornamental design for a bracket for an umbrella, as shown and described.

DESCRIPTION

FIG. 1 is a top, front and left side perspective view of a bracket for an umbrella, showing my new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The broken line showing is included for the purpose of illustrating environment and forms no part of the claimed design.
